WOMAN'S TWO-PIECE DRESS

Frances Anderman, Oak Park, Ill.

Application October 5, 1954, Serial No. 32,548

Term of patent 14 years

(Cl. D3—26)

To all whom it may concern:

Be it known that I, Frances Anderman, a citizen of the United States of America, residing at Oak Park, in the county of Cook and State of Illinois, have invented a new, original, and ornamental Design for a Woman's Two-Piece Dress, of which the following is a specification, reference being had to the accompanying drawing, forming part thereof.

Fig. 2 is another perspective view of the design of Fig. 1.
Fig. 3 is a rear perspective view thereof.

I claim:

The ornamental design for a woman's two-piece dress, as shown.
